UNITED STATES PATENT OFFICE.

EDMOND W. T. RICHMOND, OF ROMFORD, ENGLAND.

DESIGN FOR A GAS-STOVE.

SPECIFICATION forming part of Design No. 33,878, dated January 8, 1901.

Application filed December 11, 1900. Serial No. 39,558. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the rectangular body portion A, having the flat top a, upon which is arranged a frame H, containing parallel bars h, the central front portion B between pilasters C and having the

two panels D bounded by the molding d and the two end portions E of the front, each having a central panel e within the molding e', the horizontally-arranged parallel hinge members F and the horizontal latch G, the inner end of which is arranged between the hinge members.

I claim—

The design for a gas-stove, substantially as herein shown and described.

In testimony whereof I have hereunto subscribed my name.

EDMOND W. T. RICHMOND.
